AUTOMATIC NOZZLE ADJUSTMENT FOR
VACUUM CLEANERS AND THE LIKEEverett D. Thornwald, Chicago, Ill., assignor to
Clements Mfg. Co., Chicago, Ill., a corporation
of Illinois

Application July 8, 1949, Serial No. 103,708

6 Claims. (Cl. 15—359)

1

My invention relates to an improvement in vacuum cleaners and has for one purpose to provide an improved automatic nozzle adjustment for vacuum cleaners and the like for vacuum cleaners having a motor-driven brush.

Another purpose is to provide an improved nozzle structure for such vacuum cleaners.

Another purpose is to provide a floating nozzle which is adapted automatically to adjust itself to rug and carpet naps of different height and different resistance to brush action.

Other purposes will appear from time to time in the course of the specification and claims.

I illustrate my invention more or less diagrammatically in the accompanying drawings in which:

Figure 1 is a partial vertical section along the axis of movement of a vacuum cleaner;

Figure 2 is a section on the line 2—2 of Figure 1;

Figure 3 is a partial bottom view in the direction of the arrows 3—3 of Figure 2;

Figure 4 is a bottom plan view of the floating nozzle structure;

Figure 5 is a front elevation of the structure of Figure 4;

Figure 6 is an end elevation of the structure of Figures 4 and 5;

Figure 7 is a section on the line 7—7 of Figure 5;

Figure 8 is a diagram illustrating the effect of belt tension on the herein described floating nozzle structure; and

Figure 9 is a diagrammatic illustration completing, on a smaller scale, the structure of Figure 1.

Like parts are indicated by like symbols throughout the specification and drawings.

Referring to the drawings, I generally indicates any suitable ground engaging supporting wheels pivoted, as at 2, to any suitable structure 3, downwardly projecting from the upwardly and rearwardly inclined bottom wall 4 which assists in defining a suction passage extending to the suction inlet of a fan chamber 100, shown in Figure 9. Figure 9 illustrates a fan chamber 100, a fan 101 therein, a motor 102 and a pulley 103 about which passes the below described belt 41. It will be understood that the details of motor and fan do not, of themselves, form part of the present invention. The suction nozzle proper includes a rear lip 5 and a forward lip 6, the lips being connected by any suitable side walls 7, the front lip 6 and the side walls 7 being, if desired, provided with any suitable yielding element or

2

buffer strip 8. The front and rear lips 5 and 6 and the side walls 7 may be unitary with the bottom wall 4 of the suction passage, generally indicated at A in Figure 1. The passage A may include an upper wall 9. 10 is any suitable outer cover, the details of which do not, of themselves, form part of the present invention. It will be understood that the lips 5 and 6 are normally supported in predetermined relation to the floor surface X over which the vacuum cleaner rolls.

Movably mounted within the suction nozzle, but defined by the lips 5 and 6 and the side walls 7, is a movable nap engaging structure. To support it I provide inwardly extending brackets 11 suitably secured, for example, by screws 12, to any suitable boss or enlargement 13, unitary with the nozzle structure 5, 6, 7. Pivoted to the brackets 11, as at 14, are lever structures 15. Each lever 15 may be described as U-shaped, 20 having a forward bend 16 and an inwardly bent component 17. Each component 17 is slotted, as at 18, the slot having an upper enlargement 19 partly bounded by an arcuate surface 20. As shown in Figures 6 and 7, there is a difference 25 between the right-hand and left-hand levers. One of them, as shown in Figure 7, has the straight forward wall 19 at the top of the slot 18, whereas the other, as at 19a, has an arcuate walled recess. Secured to each of the forward walls 16 is a positioning spring 21.

The movable inner brush nozzle structure will next be described. As shown, for example, in Figures 4 and 5, it includes a forward lip 25 and a rear lip 26, the two lips being shown as formed of sheet metal, and as being generally upwardly channeled, as shown in Figure 1. The inner flanges 25a and 26a are of considerably less upward extension than the outer flanges 25b and 26b. The forward and rear channels are connected by suitable end walls 27. The end walls 27 are slotted, as at 28, to receive pivot pins 29 which extend therethrough from the levers 15. Thus the levers 15 are not merely pivoted to the end plates 27, but are pivoted on movable pivots 45 which permit relative longitudinal movement. Outwardly extending from each end plate 27 are guides or lugs 30, 31, which are located at different levels, and which are also located at different distances from the front of the machine. 50 Each such lug or guide enters a separate slot or channel 32, 33 which may be integral with the end walls 7 of the outer or normally fixed suction nozzle. Thus the inner floating nozzle or frame head moves vertically within the space defined 55 by the walls or lips 5, 6, 7, and, during such ver-

tical movement, the levers 15 pivot about their fixed axes 14, the slots 28 preventing any cramping action at the lower ends of the levers. Thus an adequate floating connection is provided.

34 is any suitable intermittently located wire brush guard extending in general alignment with the below described belt.

The brush structure includes the fixed shaft 35 extending into bosses 36 of end plates 37. It will be understood that the end plates, bosses and shaft do not rotate in relation to each other. 38 is a bearing block, there being one at each end of the shaft 35. 39 is a brush body rotatably mounted on bearing blocks 38 and carrying an intermediate belt slot 40 about which passes a belt 41, the opposite end of which passes about the motor and fan pulley, not herein shown.

It will be understood that when the motor is actuated its pulley, through the belt 41, rotates the brush body 39 in the direction of the arrow of Figure 1. The brush body is provided with any suitable brushes or agitating elements 42, the details of which do not form part of the present invention. It will be understood that the end plates 37 are supported on the inner component 47 of the levers 15. A ready method of support is to provide one of the bosses 36 with a flattened surface, not shown, which is adapted to engage the flattened surface 19 of the slot 18, as shown in Figure 7. The spring 21 engages the opposite side of the boss 36 and forces the flattened surface of the boss against the flat surface 19. It is not necessary to flatten both bosses, and in Figure 6 a rounded surface 19a is shown in the slot 18, which is adapted to receive the opposite, unflattened boss 36. The user can readily insert the entire brush element by merely slipping it upwardly through the slots 18, with the bosses 36 engaging the positioning springs 21. It can equally readily be removed by pulling it against the springs 21 and withdrawing it downwardly through the slots 18. Cut-outs 43 are provided at each end of the floating nozzle frame to permit passage of the bosses 36.

It will be realized that, whereas, I have described and illustrated a practical and operative device, nevertheless many changes may be made in the size, shape, number and disposition of parts without departing from the spirit of my invention. I therefore wish my description and drawings to be taken as in a broad sense illustrative or diagrammatic, rather than as limiting me to my precise showing.

The use and operation of the invention are as follows:

I provide a structure in which an outer nozzle 5, 6, 7 is normally supported at a predetermined distance from the floor or from the rug or carpet over which the cleaner is pushed. The above described sub-frame is vertically movable within the nozzle. When the motor is not actuated, it may move downwardly by gravity, or may simply rest frictionally at some position within its possible movement, within what may be called the normally fixed nozzle. But when the motor is actuated the belt 41 is moved in the direction of the arrow of Figure 1 to rotate the brush in a clockwise direction, referring to the position of the parts in Figures 1 and 8. Figure 8 is a schematic force diagram.

The lever 15 is pivoted as at 14, the point 14 being located above the resultant line of force of the dynamic belt tension. This is clear from Figure 1. Upon starting the motor, a clockwise movement is set up about the pivot point 14. 75

This movement tends to force the brush and the rug seal or floating frame downwardly toward the rug or carpet. This movement is indicated by the arrow 50 on Figure 8. When

- 5 operating on a high nap rug, the reacting force is such as to retard the downward movement of the floating frame or nozzle or rug seal. It follows, as a result, that the belt tension will increase when the brush is operating on a dense or 10 thick rug. The reacting force of the rug causes a slight decrease in the movement. The condition of equilibrium will develop, whereas the pressure on the rug will remain substantially constant, regardless of nap or weave. The slight 15 rotational displacement of the pivot arm 15 about the pivot 14, under the influence of the belt tension, causes a horizontal and vertical displacement of the connection between the pivot arm 15 and the floating stem and brush support. 20 The floating frame or seal can move only in a vertical direction, owing to its guiding connection with the fixed nozzle, by means of the projections 30 and 31. Thus a proper vertical relationship between the floating frame or rug seal and the fixed 25 nozzle structure is always maintained. At the same time, the proper vertical relationship between the rug seal and the brush is always maintained. The entire unit is readily insertable and readily replaceable.
- 30 A relatively snug fit between the fixed structure and the floating rug seal may be advantageous, to prevent air loss, or loss of cleaning efficiency, but no necessity for sealing exists. The suction, of course, should be sufficient to 35 maintain the rug or carpet somewhat upwardly withdrawn from the supporting surface X, as shown in Figure 8, and in proper contact with the brush bristles or agitator elements 42. However, the adjustment is made in response to 40 variations in the rug, and in reliance upon variations in dynamic belt tension.

I claim:

1. In a nozzle structure for suction cleaners, an outer intake nozzle and means for normally supporting it at a normally fixed and predetermined distance from the surface to be cleaned, a nozzle structure movably positioned within said normally fixed outer nozzle, means for guiding and constraining it to rectilinear, generally vertical movement within and in relation to said outer nozzle, a brush rotatably mounted on said movable nozzle, a driving belt extending about said brush, and combined supporting and actuating means for said movable nozzle including supporting levers pivoted to said outer nozzle for rotation about a single common axis located above the median line between the upper and lower stretches of said belt, said levers being pivoted to said movable nozzle generally at the axis of rotation of said brush.

2. In a nozzle structure for suction cleaners, an outer intake nozzle and means for normally supporting it at a normally fixed and predetermined distance from the surface to be cleaned, a nozzle structure movably positioned within said normally fixed outer nozzle, a brush rotatably mounted on said movable nozzle, a driving belt extending about said brush, and combined supporting and actuating means for said movable nozzle including supporting levers pivoted to said outer nozzle for rotation about a single common axis located above the median line between the upper and lower stretches of said belt, said levers being pivoted to said movable nozzle.
3. In a nozzle structure for suction cleaners,

an outer intake nozzle and means for normally supporting it at a normally fixed and predetermined distance from the surface to be cleaned, a nozzle structure movably positioned within said normally fixed outer nozzle, a brush positioned within said movably positioned nozzle structure, a driving belt extending about said brush, supporting levers for said brush, one of said levers being located adjacent each end of the brush, said levers being pivoted to and within said outer nozzle for rotation about a single common axis, and an additional guiding connection between the movably positioned nozzle structure and the outer intake nozzle formed and adapted to guide and constrain the movably positioned nozzle structure to substantially vertical, linear movement within the outer intake nozzle.

4. The structure of claim 3 characterized in that the supporting levers are pivoted to the outer nozzle for rotation about a single common axis located above the median line between the upper and lower stretches of the driving belt.

5. In a nozzle structure for suction cleaners, an outer intake nozzle and means for normally supporting it at a normally fixed and predetermined distance from the surface to be cleaned, an inner nozzle structure movably positioned within said normally fixed outer nozzle, a brush supported and mounted for rotation on said inner nozzle structure, a driving belt extending about said brush, a guiding connection between said inner nozzle structure and said outer intake nozzle, and an additional connection between the inner nozzle structure and the outer nozzle, including a lever assembly pivoted to the outer

nozzle for rotation about a single axis located above the median line between the upper and lower stretches of the belt.

- 5 6. In a nozzle structure for suction cleaners, an outer intake nozzle and means for normally supporting it at a normally fixed and predetermined distance from the surface to be cleaned, an inner nozzle structure movably positioned within said normally fixed outer nozzle, a brush supported and mounted for rotation on said inner nozzle structure, a driving belt extending about said brush, a guiding connection between said inner nozzle structure and said outer intake nozzle, and an additional connection between the inner nozzle structure and the outer nozzle, including a flexible connection having a component positioned and adapted, in response to the dynamic tension of the driving belt, to urge the movably positioned nozzle structure downwardly toward the surface on which the suction cleaner is positioned.
